UNITED STATES PATENT OFFICE.

GEORGE H. GILLIGAN, OF NEW BEDFORD, MASSACHUSETTS, ASSIGNOR TO U. S. RING TRAVELER COMPANY, A CORPORATION OF RHODE ISLAND.

TRAVELER FOR TWISTER RINGS.

Application filed November 22, 1926. Serial No. 149,837.

My invention relates to vertical ring travelers adapted for use upon vertical twister rings in distinction from the type of traveler upon rings known in this art as horizontal twister rings.

The essential objects of my invention are to prevent excess of strain and stretch of the cord being twisted; to prevent also any cramp or grip of the traveler upon the ring or any other frictional contact, and distribute any wear upon the traveler evenly; to prevent heating of the ring and rail; to lessen the amount of lubricant required; and to preserve the elasticity of the product passing beneath the traveler.

I have discovered that the recited disadvantages are largely, if not wholly, due to the tilting action of the traveler during the course around the ring whereby binding and friction results. It has been attempted to prevent such tilting by providing the upper lip of the traveler centrally with a hole for the passage of the cord, access to the hole being afforded by a vertical guide slot. In practice this means has proved only partially effective.

My present invention consists in disposing the loop or body portions of the lips in parallelism with each other as heretofore, but diagonally or at an incline to the shank of the traveler; the flanged portions or ends of the lips being thus laterally inclined relatively to the shank in opposite lateral directions, whereby in use a substantially flat bearing surface is provided thereby preventing canting of the traveler.

In the accompanying drawings which form a part of this specification

Figure 1 is a rear perspective view of my traveler operating upon a vertical twister ring,

Figure 2, a fragmentary view of the ring showing the traveler in another progressive position,

Figure 3, a section on line 3—3 of Figure 2,

Figure 4, an enlarged front elevation of the traveler, and

Figure 5, a side elevation of a modified form of my traveler. 50

Like reference characters indicate like parts throughout the views.

In the drawings 10 represents a vertical twister ring in the rail 11 of a twister frame of any usual construction wherein the ring has reciprocating vertical movement in the direction of the arrows shown in Figure 1. In this figure is also shown a portion 12 of the thread or cord which is delivered to my traveler 13 from the usual delivery rolls 60 through the ordinary fixed thread guide above the rail 11, and which passes from the traveler to the spool or bobbin as usual.

My novel traveler 13 is formed from a flat oblong metallic strip of uniform width with its ends bent oppositely to each other upon the same side of the blank, but diagonally to the blank, constituting a vertical shank 16, a loop or head 17 and a loop or foot 18. The shank in this instance has an intermediate 70 concavity 19 but this is not essential. The head 17 comprises an arched bearing portion 20, diagonally disposed relatively to the shank, and downwardly directed terminal lip 21 in a plane substantially parallel with 75 that of the shank. The foot 18 likewise includes a bearing portion 23 diagonally disposed relatively to the shank 16, parallel with the portion 20 of the head, and terminating in an upwardly directed lip 24 in a plane substantially parallel with that of the shank. Since the lips 21 and 24 are integral with the bearing portions 20 and 23 respectively the former are also diagonally disposed to the shank 16. 80

In the modified form of my invention disclosed in Figure 5 the concavity 19 of the shank 16 is omitted.

The traveler 13 with the cord or thread 12 passing under the head 17 is moved in its annular path over the ring, but because of the diagonal disposition of the head and foot of the traveler relatively to the shank the bearing portions 20 and 23 are uniformly 90 parallel with the edges of the ring 10 and therefore there is no lateral tilting or bind- 95

ing of the traveler upon the ring, and for this reason the disadvantages due to excessive friction are absent.

I claim:—

- 5 In a traveler for vertical twister rings, a substantially flat shank having its opposite ends bent outwardly at an oblique angle to said shank in directions opposite to each other and forming substantially flat bearing

surfaces across the width thereof which in use prevent canting of the traveler, and terminal lips integral with said bearing portions oppositely directed upon the same side of the shank and laterally inclined relatively thereto.

In testimony whereof I have affixed my signature.

GEORGE H. GILLIGAN.
